CHRISTMAS TREE ORNAMENT

Milton A. Fishel, New York, N. Y.

Application December 20, 1939, Serial No. 310,126

10 Claims. (Cl. 41—10)

This invention relates to Christmas tree ornaments of the type wherein the decorative element is in the form of a hollow body adapted to be suspended as a pendant from a branch or twig of the tree.

The typical Christmas tree ornament of the above type comprises a hollow bulb-like body, which is constructed of glass and includes a neck on the end of which is provided a loosely fitting cup-like cap, the bottom of which is formed with a slot adapted to receive the two normally diverging spring-like arm portions of a loop-like fastening device, through the eye of which may be looped a relatively short length of wire adapted to function as a suspension device by which the ornament may be attached to the branch or twig of the tree, the bulb-like body together with the cup-like cap and loop-like fastening device being held in an assembled relation by reason of the fact that the diverging arm portions of the fastening device impinge against the inner wall of the bulb-like body at or in the vicinity of the juncture of said neck with the main portion of said body.

In an ornament of the type generally described above, the cup-like cap is employed somewhat for the sake of appearance and somewhat as a protective covering for the outer end of the neck which, like the main portion of the bulb-like body, is of an extremely fragile character; but such cap does not in any way cooperate with the loop-like fastening device or the bulb-like body in effecting a positive, dependable and reliable interconnection between such body and fastening device, with the result that these two elements are frequently unduly and unintentionally separated as will be readily understood when it is taken into account that only a very slight pull exerted on these elements in opposite directions is necessary to so spring the diverging arm portions of the fastening device as to permit them to pass freely out of the bulb-like body by way of the neck thereof. Indeed, the connection afforded between the bulb-like body and the loop-

like fastening device is often so ineffective that the weight of the extremely light body, when suspended in its decorative position on a tree, is sufficient to cause the arm portions of the fastening device to so yield as to permit the body to become detached from its associated fastening device, with the result that such body falls by gravity and is broken. In certain instances separation of the bulb-like body from its associated fastening device occurs under such conditions

claimed in an unharmed or substantially unharmed condition, whereupon it becomes necessary to re-attach the fastening device to render the ornament usable. It is customary, however, before re-attaching the fastening device to spring the arm portions of that device farther apart so as to increase the holding effect of the same, assuming they can be successfully re-inserted through the neck of the ornament, but the intensified spring action of the more widely separated arm portions of the fastening device not only makes the insertion of the fastening device more difficult but also enhances the likelihood of fracturing or breaking the neck, in an attempt to effect such insertion, as will be readily understood when it is taken into account that preparatory to reassembling the ornament the arm portions are sprung together, whereupon they are introduced into the outer end of the neck and released, with the result that the outwardly directed force which they, when so released, exert on the inner wall of the neck fracture or break such neck before an opportunity is had to move the fastening device to its final position within the bulb-like body. Once such breakage of even only the outer end portion of the neck occurs, further attempts to assemble the ornament are even more difficult to effect without breakage than in the first instance.

Important objects of the present invention are to overcome the above-mentioned defects which are peculiar to conventional Christmas tree ornaments of the general type to which this invention pertains and to obviate the difficulties heretofore encountered because of such defects.

To the above and other ends the invention contemplates a bulb-like body in association with a suspension device, which may be directly attached to a branch or twig of a Christmas tree and is connected to said bulb-like body through the medium of an anchoring device carried by said bulb-like body and effectively maintained against undue displacement with relation to such body.

Other objects and advantages of the invention will become apparent from the following description when taken in connection with the accompanying drawing, in which—

Fig. 1 is a side elevation of a bulb-like body for use in Christmas tree ornaments constructed in accordance with the present invention;

Fig. 2 is a side elevation of an anchoring device adapted to be attached to the neck of the bulb-like body of Fig. 1 and to be normally held against displacement with relation to such body;

Fig. 3 is an enlarged transverse sectional view of the anchoring device of Fig. 2;

Fig. 4 is a transverse sectional view of the anchoring device, the section being taken on line 5 4-4 of Fig. 3;

Fig. 5 is a side elevation of a suspension device for use in association with the anchoring device of Figs. 2 to 4;

Fig. 6 is a side elevation of a Christmas tree 10 ornament constructed in accordance with the present invention and including the bulb-like body of Fig. 1, the anchoring device of Figs. 2 to 4 and the suspension device of Fig. 5, the suspension device being illustrated as attached to a 15 branch or twig of a Christmas tree from which the ornament is suspended, and

Fig. 7 is a view similar to that of Fig. 4 and showing a slightly modified form of anchoring device.

Although the decorative elements of Christmas tree ornaments constructed in accordance with the present invention may be so formed or fabricated as to present various geometrical configurations, the decorative element herein illustrated is of a simple geometrical contour in the form of a hollow bulb-like body 10 which is constructed of suitable material, such as glass which is colored or otherwise treated to present an attractive and pleasing optical effect. The bulb-like body 10, which includes a neck 11, may be blown or otherwise formed so as to provide on the outer end of the neck 11 an external screw-thread 12, or the equivalent of such thread, adapted to so cooperate with an anchoring device such as is indicated by the numeral 14 in Figs. 2, 3, 4 and 6. The anchoring device 14 consists of a thin-gauge metal cap, the side wall 15 of which is provided with a screw-thread 16, or the equivalent thereof, and the end wall 17 of which is sheared along parallel lines between which is struck out a yoke-like rib 18 serving as a suspension-device-receiving element.

The anchoring device 14 is so dimensioned as to enable it to be readily applied to the neck 11 of the bulb-like body 10, and in view of the complementary relationship of the screw-threads 12 and 16 it follows that these threads function as means for directly attaching the anchoring device to the bulb-like body and for normally maintaining such device against displacement with relation to such body.

In order that the ornament may be readily attached to a branch or twig of a Christmas tree and effectively held in its decorative position, a 55 suspension device 20 is provided for use in association with the anchoring device 14. The suspension device 20 comprises a coil spring 21, the convolutions of which normally lie in a close contiguous relation to each other but are adapted 60 to be sprung apart, as shown in Fig. 5, so as to permit the ready reception therebetween of a Christmas tree branch or twig 22 against which adjacent convolutions of the spring are adapted to normally impinge with sufficient force to securely attach the suspension device to the branch or twig. As shown most clearly in Fig. 5, the spring 21 terminates at one end in a loop 24 and at its opposite end in a loop-like latch 25, the free arm 26 of which is provided at its extreme 65 end with a hook-like keeper 27. The resiliency of the latch 25 is such that its free arm 26 is, when unlatched, so separated from the spring 21 as to permit it to be readily passed under the yoke-like rib 18 of the anchoring device 14 in attaching the 70 suspension device to the anchoring device with

which is associated the bulb-like body 10 when the ornament is in its final or completely assembled condition. After attaching the suspension device to the anchoring device in the manner thus far described, the latch 25 may be closed by pressing the arm 26 to such position as will permit that arm upon the release of pressure to spring outwardly into interlocking engagement with that convolution with which the latching device is directly associated, whereupon the keeper, due to its overlying relation to such convolution, becomes effective to hold the arm 26 against such displacement as would result in undue opening of the latch 25.

If desired, the form of anchoring device shown 15 in Fig. 7 and there indicated by the numeral 14' may be substituted for the anchoring device 14. The anchoring device 14' differs from the anchoring device 14 only insofar as the type of suspension-device-receiving element is concerned. 20 In this connection it will be observed that the suspension-device-receiving element of the anchoring device 14' comprises a rib-like lobe 28 which is struck up from the end wall 17' and is so pierced as to provide an aperture 30 adapted 25 for the reception of the latch 25 of the suspension device 20, which suspension device, when used in association with the anchoring device 14', is adapted to function in a manner identical with that described in connection with the anchoring device 14.

From the foregoing description, it will become apparent that an ornament constructed in accordance with the present invention may be readily attached to or detached from a branch or twig 35 of a Christmas tree by springing apart the convolutions of the spring 21 a sufficient distance to permit the branch or twig to be received therebetween or removed therefrom, as the case may be, the loop 24 being adapted, as will be 40 readily understood, to facilitate such stretching of the spring as is required to effect that degree of separation of the convolutions as is necessary to accommodate the Christmas tree branch or twig or permit the removal of such branch or 45 twig.

Moreover, it is to be noted that the present invention is such that the defects herein pointed out as peculiar to the conventional type of Christmas tree ornaments are eliminated because of the fact that the suspension device, which is adapted 50 to be attached to a branch or twig of a Christmas tree, is connected to the bulb-like body of the ornament through the medium of an anchoring device carried by that body and effectively maintained against undue displacement with respect to such body.

Aside from the advantages herein particularly described as peculiar to the present invention, it is to be observed that the invention is such that 60 fewer parts are required than in the conventional type of Christmas tree ornaments, particular reference being had to the elimination of the above-mentioned ineffective and unreliable loop-like fastening device of the prior art.

It will be understood that various structural changes other than those herein particularly pointed out may be made without departing from the spirit of the invention or the scope of the following claims.

What is claimed is:

1. A Christmas tree ornament comprising a decorative element, an anchoring device carried by said decorative element, means cooperating with said decorative element and said anchoring 75

- device for maintaining said element and said device against displacement with relation to each other, and a suspension device connected to said anchoring device and adapted to be attached to a branch or twig of a Christmas tree whereby the ornament may be suspended in decorative position.

2. A Christmas tree ornament comprising a decorative element in the form of a bulb-like body having a neck, an anchoring device associated with said neck, means cooperating with said neck and with said anchoring device for maintaining said decorative element and said device against displacement with relation to each other, and a suspension device connected to said anchoring device and adapted to be attached to a branch or twig of a Christmas tree whereby the ornament may be suspended in decorative position.

3. A Christmas tree ornament comprising a decorative element, an anchoring device carried by said decorative element, interlocking means provided in part on said decorative element and in part on said anchoring device for maintaining said element and said device against displacement with relation to each other, and a suspension device connected to said anchoring device and adapted to be attached to a branch or twig of a Christmas tree whereby the ornament may be suspended in decorative position.

4. A Christmas tree ornament comprising a decorative element in the form of a bulb-like body having a neck, an anchoring device associated with said neck, interlocking means provided in part on said neck and in part on said anchoring device for maintaining said decorative element and said device against displacement with relation to each other, and a suspension device connected to said anchoring device and adapted to be attached to a branch or twig of a Christmas tree whereby the ornament may be suspended in decorative position.

5. A Christmas tree ornament comprising a decorative element, an anchoring device carried by said decorative element, means cooperating with said decorative element and said anchoring device for maintaining said element and said device against displacement with relation to each other, and a suspension device in the form of a coil spring connected to said anchoring device, convolutions of which spring are adapted to receive therebetween and impinge on a branch or twig of a Christmas tree whereby the ornament may be suspended in a decorative position.

6. A Christmas tree ornament comprising a decorative element in the form of a bulb-like body having a neck, an anchoring device associated with said neck, means cooperating with said neck and with said anchoring device for maintaining said decorative element and said device against displacement with relation to each other, and a suspension device in the form of a coil spring connected to said anchoring device, convolutions of which spring are adapted to receive therebetween and impinge on a branch or twig of a Christmas tree whereby the ornament may be suspended in a decorative position.

7. A Christmas tree ornament comprising a decorative element, an anchoring device carried by said decorative element, means cooperating with said decorative element and said anchoring device for maintaining said element and said device against displacement with relation to each other, and a suspension device in the form of a coil spring terminating at one end in a loop-like latch having an interlooped connection with said anchoring device and including an arm adapted to maintain interlocking connection with said spring, convolutions of which spring are adapted to receive therebetween and impinge on a branch or twig of a Christmas tree whereby the ornament may be suspended in a decorative position.

8. A Christmas tree ornament comprising a decorative element in the form of a bulb-like body having a neck, an anchoring device associated with said neck, means cooperating with said neck and with said anchoring device for maintaining said decorative element and said device against displacement with relation to each other, and a suspension device in the form of a coil spring terminating at one end in a loop-like latch having an interlooped connection with said anchoring device and including an arm adapted to maintain interlocking connection with said spring, convolutions of which spring are adapted to receive therebetween and impinge on a branch or twig of a Christmas tree whereby the ornament may be suspended in a decorative position.

9. A Christmas tree ornament comprising a decorative element, an anchoring device carried by said decorative element, interlocking means provided in part on said decorative element and in part on said anchoring device for maintaining said element and said device against displacement with relation to each other, and a suspension device in the form of a coil spring terminating at one end in a loop-like latch having an interlooped connection with said anchoring device and including an arm adapted to maintain interlocking connection with said spring, convolutions of which spring are adapted to receive therebetween and impinge on a branch or twig of a Christmas tree whereby the ornament may be suspended in a decorative position.

10. A Christmas tree ornament comprising a decorative element in the form of a bulb-like body having a neck, an anchoring device associated with said neck, interlocking means provided in part on said neck and in part on said anchoring device for maintaining said decorative element and said device against displacement with relation to each other, and a suspension device in the form of a coil spring terminating at one end in a loop-like latch having an interlooped connection with said anchoring device and including an arm adapted to maintain interlocking connection with said spring, convolutions of which spring are adapted to receive therebetween and impinge on a branch or twig of a Christmas tree whereby the ornament may be suspended in a decorative position.
